DESCRIPTION

FIG. 1 is a front view of a tire for automobile showing my
new design;

FIG. 2 is a rear view thereof;

FIG. 3 is a top plan view thereof;

FIG. 4 is a right side view thereof;

FIG. 5 is a left side view thereof; and,

FIG. 6 is a perspective view thereof.

In the drawings, the dark stippled surface shading represents
the recessed portion of the tread grooves, having the depth
shown at the top and bottom of FIGS. 1-3.
